UNITED STATES PATENT OFFICE.

STACY B. HASELTINE, OF CHICAGO, ILLINOIS, ASSIGNOR TO WILLIAM H. MINER, OF CHAZY, NEW YORK.

SIDE BEARING FOR CARS.

1,179,721.

Specification of Letters Patent. Patented Apr. 18, 1916.

Application filed April 5, 1915. Serial No. 19,353.

To all whom it may concern:

Be it known that I, STACY B. HASELTINE, a citizen of the United States, residing at Chicago, in the county of Cook and State of Illinois, have invented a certain new and useful Improvement in Side Bearings for Cars, of which the following is a full, clear, concise, and exact description, reference being had to the accompanying drawings, forming 10 a part of this specification.

This invention relates to improvements in side bearings for cars.

An object of the invention is to provide a roller side bearing for railway cars which 15 consists of few parts, readily assembled, relatively cheaply manufactured, and in which spring means aided by gravity are employed to always return the roller to its central normal position after each actuation.

20 The invention furthermore consists in the improvements in the parts and devices and in the novel combinations of the parts and devices, as herein shown, described or claimed.

25 In the drawing forming a part of this specification, Figure 1 is an end elevation of a portion of a body bolster and a truck bolster showing my improvements in connection therewith. Fig. 2 is a top plan view of my 30 improved roller bearing. Fig. 3 is a vertical sectional view taken on the line 3—3 of Fig. 1 and Fig. 4 is a vertical sectional view taken on the line 4—4 of Fig. 2.

In said drawing, 10 denotes the body bolsters and 11 the truck bolsters pivotally connected in the usual manner and between which is mounted my improved roller side bearing designated generally by the reference A. As shown, said bearing is attached 40 to the truck bolster but it may be otherwise attached, as those skilled in the art will understand.

The roller bearing A, as shown, comprises a base casting 12 having upwardly extended, 45 spaced side walls 13—13 and a bottom steel plate insert tread or roller bearing surface 14. Each of the side walls 13, on its inner face, is provided with a longitudinally extending recess 15, the same having flat bottom walls 16, upper flat walls 17 and rounded end walls 18, the upper walls 17 being cut away to form openings 19 through which the trunnions 20 of the anti-friction roller 23 are adapted to be inserted. Mounted in 50 each of the recesses 15 is a plate spring 21

having portions thereof inclined upwardly from the center and on both sides thereof, said upwardly inclined portions each terminating in a curved end 22 fitting against the end walls of the recess 15. As clearly shown 60 in Figs. 3 and 4, the springs 21 are interposed between the studs 20 and the lower flat walls 16 of the recesses.

The operation is as follows: Upon pressure being applied to the roller 23 and angular movement between the bolsters, the roller 23 will roll upon the tread plate 14 and thus move to one side of its central or normal position. In so doing, the studs 20 will depress those upwardly inclined portions of the springs 21 over which they roll and against the tension of the spring. Upon release of the pressure on the roller 23, the springs 21—21 which have been pressed down or straightened will immediately return to their normal position which is indicated in Fig. 3 and thus elevate the roller 23 from engagement with the bearing plate 14. The roller 23 being now supported by its trunnions 20 on the inclined portions of the springs 21, which thus form inclined tracks, will roll under the influence of gravity back to its central normal position. It is apparent that the above described action takes place in whichever direction the roller is moved.

As clearly shown in Fig. 3, the tread of wear plate 14 is beveled at its ends as indicated at 24 and the length of the wear plate 14 is made such that the anti-friction roller will always bear thereon within the limits of normal movement between the bolsters. Upon excessive movement, however, the anti-friction roller will pass off of the wear plate and be supported by its own trunnions 20—20 in the side walls of the base casting so that the roller will rotate about its own trunnions, under excessive movement, without being bodily moved. In this way, I provide a compact bearing and yet make provision for any amount of movement between the bolsters.

I claim:

1. In a roller side bearing for railway cars, the combination with a base casting having a roller carried thereby and adapted to roll back and forth therein, said roller having trunnions, of spring means for returning said roller to central position after each actuation thereof, said means including a

spring plate extending transversely of the axis of the roller and located at the end of the roller, said spring plate being inclined upwardly on both sides of its center and engaging the trunnion whereby, as the roller moves from its central position the spring plate will be deflected and upon release of the pressure on the roller the spring will elevate the roller and the latter return to central position by gravity.

2. In a roller side bearing for railway cars, the combination with a base casting having spaced, upwardly extending side walls and a roller tread surface therebetween, of a roller mounted between said side walls and having trunnions movable back and forth in recesses formed on the inner faces of said walls, and springs located within said recesses and engaging said trunnions arranged to return the roller to normal after actuation thereof.

3. In a roller side bearing for railway cars, the combination with an anti-friction

roller having trunnions, of vertically arranged members at the sides of said roller having longitudinally extending recesses therein in which said trunnions are adapted to move back and forth, and plate springs mounted in said recesses and extending beneath said trunnions, each of said plate springs being inclined upwardly on each side of the center thereof whereby as the roller moves from its central position the plate springs will be depressed and upon release of the pressure on the roller, said depressed portions of the plate springs will assume their normal position and elevate the roller, the roller then returning under the influence of gravity to central position.

In witness that I claim the foregoing I have hereunto subscribed my name this 24th day of March 1915.

STACY B. HASELTINE.
